UNITED STATES PATENT OFFICE

JOHN F. ROGERS, OF CLEVELAND HEIGHTS, OHIO, ASSIGNOR TO THE WELLMAN ENGINEERING COMPANY, OF CLEVELAND, OHIO, A CORPORATION OF OHIO

MECHANICAL FEED FOR GAS PRODUCERS

Application filed May 2, 1925. Serial No. 27,379.

This invention relates to mechanical feeders and particularly to feeders of the automatic type for supplying fuel at the desired rate to gas producers.

For the proper operation of gas producers it is desirable that the fuel be delivered into the producer at a uniform rate corresponding to the rate at which the fuel is consumed in the producer. It is also desirable that the fuel feeding means be such that gas will not be permitted to escape through the feeder. In order to insure proper distribution of fuel upon the top of the fuel bed, the fuel should be delivered to the producer in relatively small quantities and at relatively short intervals.

Heretofore great difficulty has been experienced in designing feeders for gas producers capable of maintaining the proper feed of fuel and of providing an efficient seal against the escape of gas due to the fact that the producer gases contain large quantities of tarry substances which condense upon the feeding elements tending to clog the same.

In feeders heretofore used it has been necessary to provide special means for clearing the sticky condensates from the feeding elements and such condensates have so greatly increased the friction between relatively moving parts of the feeders that considerable power has been required to operate the feeders and the feeding elements have been subjected to severe wear.

It is an object of the present invention to provide a feeder which satisfies the requirements as to regularity of feed and prevention of escape of gas but in which the operation is not hindered by the substances condensing from the producer gases.

Further objects are to provide a feeder requiring very little power to operate, to provide a feeder in which the parts are subjected to very little wear due to friction and to provide a feeder of light construction which is inexpensive to manufacture.

A further object is to provide an automatic feeder in which the delivery of fuel into the producer is controlled by a bell which is mounted in a chamber in the feeder casing entirely above the cover of the producer so

that it is protected from the heat of the producer.

A further object is to provide a feeder of the double bell and hopper type having a casing so constructed that access may be readily had to the bells for the purpose of repairing or replacing them and further to provide means by which the feeder casing may be cut off from the interior of the producer to permit repair of the feeder while the producer is in operation.

With the above and other objects in view, the invention may be said to comprise the feeder as illustrated in the accompanying drawings, hereinafter described, and particularly set forth in the appended claims together with such variations and modifications thereof as will be apparent to one skilled in the art to which the invention appertains.

Reference should be had to the accompanying drawings, forming a part of this specification, in which Fig. 1 is a fragmentary section through the top of a gas producer showing the feeder in side elevation; Fig. 2 is a side elevation of the feeder as viewed from the side opposite that shown in Fig. 1; Fig. 3 is a vertical section through the feeder casing; Fig. 4 is an enlarged detail view showing the pawl and ratchet mechanism for operating the cam shaft; Fig. 5 is an enlarged detail view showing the pawl which engages the feeder ratchet and the releasable retaining means for the pawl; Fig. 6 is a rear elevation of the ratchet actuating mechanism; Fig. 7 is a side elevation showing a feeder provided with an operating motor mounted on the base thereof; Fig. 8 shows a modified form of actuating pawl and restraining device for the cam shaft ratchet; and Fig. 9 shows a modified form of automatically releasable pawl for the feeder ratchet.

Referring to the accompanying drawing, Fig. 1 shows the upper portion of the body 1 of a gas producer and the cover 2 mounted upon the top of the producer body. The body 1 and cover 2 are ordinarily rotatable one with respect to the other, a suitable water seal 1^a being provided between the upper edge of the wall of the producer body and the

periphery of the cover. One or more feeders are mounted upon the cover 2 and these feeders discharge on to different portions of the fuel bed during the rotation of the producer body.

The feeder, forming the subject matter of the present invention, as shown in Figs. 1, 2 and 3, is provided with a base section 3 which is secured upon the top of the cover 2, this base section 3 being provided with a central opening 4 through which the fuel is discharged into the producer, the section 3 also having an upwardly flaring wall 5 which surrounds the opening 4 and extends upwardly therefrom. At its upper edge the wall 5 has an outturned flange 6 upon which is secured the intermediate section of the feeder casing. The intermediate section is formed of front and rear halves 7 and 8, which are provided with base flanges 9 and 10 adapted to be bolted upon the flanges 6 of the base section and with abutting vertical flanges 11 and 12 adapted to receive bolts for securing the two halves together. The lower portion of the intermediate section is restricted by a downwardly tapering conical wall portion 13 which terminates in a discharge opening 14 directly above the opening 4 into the producer. The front and rear portions 7 and 8 of the intermediate section are provided with outturned flanges 15 and 16 at their upper ends which form supports for the base flange 17 of the top section 18 of the casing.

The flange 16 of the portion 8 of the intermediate section of the casing has threaded therein vertical jack screws 19, the upper ends of which bear against the under side of the flange 17 of the upper section and by means of which the upper section 18 may be lifted when the attaching bolts are loosened to free the front section 7 of the casing and permit the same to be removed without disturbing the section 8, for a purpose which will hereinafter be more fully explained.

Since the tarry condensates may work in between the attaching flanges and cause the sections of the casing to stick tightly together after the bolts are removed, the flanges 11 and 12 are notched to provide between them a recess or socket 20 adapted to receive the point of a chisel or other suitable tool for breaking the portion 7 loose after its attaching bolts have been removed.

The upper section 18, of the casing, has a downwardly tapering lower end portion 21 which terminates in an opening 22 through which material is discharged from the upper section into the intermediate section. Adjacent the lower portion thereof, the wall of the upper section 18 is bulged outwardly at 23 and adjacent the lower end, the wall of the intermediate section has a corresponding outward bulge at 24. Horizontal shafts 25 and 26 extend transversely through the outwardly bulged portions 23 and 24 of the cas-

ing and these shafts have fixed thereto, within the casing, inwardly extending arms 27 and 28 from which are suspended links 29 and 30 and to the lower ends of the links 29 and 30 are attached bells 31 and 32, which are adapted to open and close the discharge openings 22 and 14. Upon the outside of the casing, at one side thereof, the shafts 25 and 26 have fixed thereto levers 33 and 34 to the outer ends of which are attached counterweights 35 and 36, the counterweights 35 and 36 acting to turn the shafts 25 and 26 in a direction to hold the bells 31 and 32 in closed positions.

The upper lever 33 has an integral downwardly and outwardly extending arm 37 and the lever 34 has an upwardly and inwardly extending arm 38, the arms 37 and 38 having rollers 39 and 40 which engage with a cam 41 carried by a horizontal shaft 42 journaled in the casing between the shafts 25 and 26, the rollers 39 and 40 being arranged to engage the cam upon opposite sides of the shaft. The cam 41 is provided with an outwardly projecting arm 43 which, during the rotation of the cam, engages alternately with the rollers 39 and 40 to alternately swing the levers 33 and 34 in a direction to lift the counterweights and to move the bells 31 and 32 to open position.

Means is provided for rotating the cam shaft 42 at the proper rate to operate the bells at definite predetermined time intervals and to this end the cam shaft 42 has fixed thereto, at the end thereof opposite that carrying the cam and upon the opposite side of the casing, a ratchet 44 in the form of a spur gear formed with involute teeth. The ratchet 44 is actuated by means of a pawl 45 carried by a vertically disposed link 46 which is connected at its lower end to an arm 47 which is fixed to and extends forwardly from a horizontal rock shaft 48 journaled in bearing brackets 49 fixed to the lower portion of the part 8 of the intermediate section of the casing and at its upper end to an arm 50 which extends rearwardly from a stub shaft 51 carried by the upper section 18 of the casing. The shaft 48 has fixed thereto an actuating arm 52 to which is attached a connecting rod 53 which is intermittently actuated by a crank or eccentric which may be driven by any suitable mechanism, either from the producer rotating mechanism or by an individual motor as shown in Fig. 6 in which the rod 53 is connected to a crank 54 fixed to a shaft 55 driven by an electric motor 56 through suitable reduction gearing in a casing 57, the motor 56 and casing 57 being mounted upon a platform 58 extending from the base of the feeder casing. In each revolution of the crank or eccentric, the link 46 is moved up and down and through the pawl 45 imparts a predetermined angular movement to the cam shaft 42.

To impart the necessary vertical movement

to the bells and to provide relatively fast opening and closing movements the cam arm 43 is preferably a long narrow arm which engages each of the counterweight levers only while the cam is turning through a relatively small portion of its revolution. While the front face of the arm 43 engages with a counterweight lever the weighted end of the lever is lifted and, while the engaging roller of the lever is riding down the rear face of the cam, the counterweight acts upon the arm tending to turn the cam shaft in a direction to cause the ratchet 4 to overrun the pawl. In order to accurately time the movements of the bells it is, therefore, highly important that a pawl and ratchet mechanism be provided which will prevent movement of the ratchet in either direction during the return stroke of the pawl carrier and which will prevent overrunning of the ratchet during the active stroke. The pawl and ratchet mechanism is illustrated in Figs. 1 and 4 of the drawings and includes in addition to the actuating pawl 45 and ratchet 44 a holding pawl 59 suspended from the shaft 25 and a second holding pawl 60 carried by the link 46.

The pawl 45 is connected to the link 46 by a horizontal pivot 61 and has a curved arm 62 extending upwardly from the pivot 61 and terminating in a ratchet engaging tooth 63. The pawl also has an arm 64 extending out from the pivot 61 and carrying a counterweight 65 at its outer end for rocking the pawl in a direction to engage the tooth 63 with the teeth of the ratchet 44, the tooth 63 has a lower face 63^a formed to positively engage the teeth of the ratchet on the down stroke of the link 46 to turn the ratchet, and an upper face 63^b so formed that when moved upwardly with the link 46 it will engage the ratchet tooth in its path at an inclination such that the thrust on the pawl has an outward component tending to shift the arm 62 in opposition to its counterweight 65 away from the ratchet to permit the tooth 63 to pass a tooth of the ratchet on the up stroke. The holding pawl 59, which is suspended from the shaft 25 directly over the cam shaft 42, tends to move by gravity into ratchet engaging position, and has, at its lower end, a ratchet engaging tooth 66 which has an upper face 66^a formed to have a locking engagement with a ratchet tooth engaging therewith to positively lock the ratchet against turning in a direction opposite that in which the ratchet is turned by the pawl 45. The lower face 66^b of the tooth 66 is beveled at an angle such that as the ratchet is actuated by the pawl 45 the pawl 59 is swung outwardly to permit the teeth of the ratchet to pass the tooth 66. The pawl 59 serves to lock the ratchet against reverse rotation during the return movement of the pawl 45. The second holding pawl 60 is connected at its upper end by a pivot 67 to a projecting portion

46^a of the link 46 and has a ratchet engaging tooth 68 at its lower end, the pivot 67 being disposed over the ratchet so that the pawl 60 tends to move by gravity to engaging position. The tooth 68 of the pawl 60 is formed to have a locking engagement with the teeth of the ratchet to prevent movement of a tooth past the same in the direction in which the ratchet is moved by the pawl 45. The pawl 60 moves with the actuating pawl 45 and engages with the ratchet during the active stroke of the pawl 45 to prevent overrunning of the ratchet. The pawl 45 is so mounted on the link 44 that the tooth 63 thereof at the end of the down stroke lies substantially at the level of the shaft 42 which carries the ratchet so that during the down stroke the tooth arm 62 swings outwardly from the axis of the ratchet. This movement of the arm 62 is utilized to free the tooth 68 of the pawl 60 at the end of the down stroke, the pawl 60 having a pin 70 with which the arm 62 engages during the downward movement thereof and the pin engaging edge of the arm being so curved that the tooth 68 is moved to a position clear of the ratchet at the end of the down stroke so that the tooth 68 of the pawl will ride over the tooth of the ratchet immediately above it during the return or up stroke of the link 46. During the down stroke of the link 46 the ratchet is turned by the pawl 45 and held against overrunning by pawl 60. At the end of the down stroke the pawl 60 is freed from the ratchet and the tooth 66 of the pawl 59 drops into engagement therewith. The pawl 59 locks the ratchet against rotation in a direction reverse to that imparted thereto by the pawl 45 on the down stroke thereof and takes the thrust imparted by the upper face 63^b of the tooth 63 during the upward stroke, the face 63^b of the tooth 63 exerting a pressure on the ratchet tooth with which it engages and serving to prevent rotation of the shaft 42 in a forward direction during the return stroke of the pawl. As the link 46 approaches its upper limit of movement the tooth 68 of the pawl 60 drops into ratchet engaging position and the tooth 63 of the pawl 45 rides over the end of the ratchet tooth with which it has been engaging and drops into engagement with the rear face of the tooth. It should be noted that the tooth 63 of the pawl 45 when in engagement with the ratchet, lies to the same side of the pivot 61 of the pawl as the counterweight 65 and the lower engaging face 63^a thereof is so disposed that the thrust against the ratchet tooth during the downward stroke has a component acting in a direction to press the arm 62 toward the ratchet and hold the tooth 63 in engagement with the ratchet. In Fig. 8 of the drawing there is shown a modified form of pawl and ratchet designed to prevent overrunning and reverse rotation of the

cam shaft. In this modification the ratchet 44 and holding pawl 59 are the same as in the modification above described and the ratchet operating means is carried by the same link 46. The actuating pawl 71 is suspended at its upper end by a pivot 72 from the link 46 and has an engaging tooth 73 formed to have a driving engagement with the ratchet teeth during downward movements of the link. The pawl 71 has also a counterweight 74 acting to move the pawl toward engaging position, the counterweight having a lug 75 engageable with the link 46 to limit the movement thereof toward the ratchet. For preventing overrunning of the ratchet, a leaf spring 76 is fixed at its upper end to the link 46 and has its lower end positioned to engage the teeth of the ratchet during the active stroke of the link 46. The spring 76 yields as the ratchet is turned by the pawl 71 but has sufficient strength to hold the ratchet from overrunning the actuating pawl. The fuel is delivered to the upper bell 31 by means of a vane wheel 76 which is offset to one side of the longitudinal axis of the casing, the casing wall having an offset portion 77 in the form of a segment of a cylinder concentric with the axis of the vane wheel and the wheel has radial vanes 78 the edges of which are in close proximity to the cylindrical surface of the offset portion as they pass the same to cut off flow of fuel along the casing wall. The casing is provided with an inlet 79 at its upper end which is offset laterally to a greater extent than the vane wheel 76 so that the angle of repose of the material entering through the inlet 79 and resting upon the casing wall and upon the vane wheel, is such that the top surface of the material lies below the top of the vane wheel whereby the only fuel fed to the upper bell will be that carried around in the pockets between the vanes 78. The flow of fuel through the inlet 79 may be controlled by a slide valve 80 operated by any suitable means, the valve, as shown herein, being provided with a rack 81 engaged by a pinion 82 adapted to be turned by a hand wheel 83. The vanes 78 may be provided with retaining fingers 84 which retard the discharge of fuel so that the vane wheel will deliver the material in a substantially continuous stream to the bell 31. The vane wheel 76 regulates the flow of fuel to the upper bell 31 and, to this end, means is provided for turning the vane wheel at various rates of speed relatively to that of the bell actuating cam shaft. In order to maintain at all times a fixed ratio between the rates of movement of the cam shaft 42 and the vane wheel 76 the vane wheel is actuated by a pawl and ratchet mechanism which is operated by the link 46 which operates the cam shaft ratchet 44. A ratchet 85

in the form of a spur gear is fixed to the vane wheel shaft 76^a outside the feeder casing and this ratchet is operated by a pawl 86 carried by an arm 87 which is rotatably mounted on the shaft 76^a alongside the ratchet. The arm 87 is connected by a link 88 with a nut 89 which is adapted to travel along a screw 90 mounted in an extension 50^a of the arm 50 to which the upper end of the link 46 is attached. The arm 50^a is rocked upon each actuation of the link 46 and through the link 88 imparts an oscillating movement to the pawl arm 87 which through the pawl 86 imparts a turning movement to the ratchet 85. The screw 90 carries at its forward end a hand wheel 91 by means of which the screw may be rotated to adjust the nut along the same and toward and from the pivotal axis of the arm to vary the throw of the pawl arm 87 and to increase or decrease the angle through which the vane wheel is turned upon each actuation of the link 44. The pawl 86 is rotatably mounted upon a pivot pin 92 carried by the arm 87 adjacent its outer end, the pivot pin 92 being parallel with the vane wheel shaft 76^a and extending across the periphery of the ratchet 85. The pawl 86 has a tooth 93 in the form of a gear tooth adapted to mesh with the teeth of the ratchet and to roll into and out of engagement therewith. The pawl is provided with a counterweighted arm 94 which acts to turn the pawl about its pivot in a direction to swing the tooth 93 into engagement with the ratchet at the end of the return stroke of the arm 87. Movement of the pawl about its pivot in the direction toward which it is urged by the counterweight is limited by a stop pin 95 which projects through a laterally bent end portion 96 of the arm 87, which overlies the outer side of the pawl 86, and engages with an outwardly projecting lug 97 on the pawl 86. When the lug 97 of the pawl engages the pin 95 the tooth 93 is in ratchet engaging position, the pawl being held by the pin in engaging position during the forward stroke of the arm 87 to impart movement to the ratchet. Upon the return stroke of the ratchet the pressure of the tooth 93 against a tooth of the ratchet swings the pawl in a direction to move the lug 97 away from the pin 95 and to lift the counterweight arm 94, permitting the tooth 93 to ride over the teeth of the ratchet. The pin 95 is preferably of bendable material which upon the exertion of a pressure in excess of a predetermined amount will yield and permit the lug 97 to pass and thus free the pawl from the ratchet. As shown herein, the pin 97 is simply a nail of the size required to offer the desired resistance to bending. In the event that the rotation of the vane wheel should be impeded to such an extent that there is danger of damage either to the actuating mechanism or to the

vanes, the pin 97 will bend and automatically release the pawl 86 from the ratchet. When so released the arm 87 will oscillate idly without turning the vane wheel. The operator may then remove the obstruction impeding the rotation of the vane wheel and replace the nail 97 with a straight nail whereupon the operation of the vane wheel will be resumed. For permitting ready access to the vane wheel 76 the front of the top section 18 of the casing may be provided with a door 98.

Fig. 9 of the drawing, shows a modified form of automatically releasable pawl for operating the vane wheel ratchet. In this modification a pawl carrying arm 99 is pivoted directly upon the nut 89 on the screw 90 carried by the extension 50^a of the arm 50 and this pawl arm 99 carries at its upper end a pawl 100 which is connected thereto by means of a pivot 101 the pawl 100 being provided with a downwardly projecting finger 102 which engages with a stop pin 103 carried by the arm to hold the pawl in proper engaging position. Yielding means is provided for holding the pawl in a position in which the finger 102 engages with the stop pin 103, and this means consists of an arm 104 suspended from a pivot 105 a short dis-

tance below the stop pin 103 on the arm 99. The arm 104 is provided with an upwardly extending finger 105 which engages with the finger 102 of the pawl and at its lower end carries a counterweight 106 which normally lies within an opening 107 formed in the arm 99. It sometimes happens that a bar of wood or iron or other foreign matter is fed to the vane wheel, with the fuel, and becomes jammed between the vane wheel and casing, preventing the rotation of the wheel.

Whenever the rotation of the vane wheel is thus impeded the pawl 100 upon downward movement of the arm 99 will rock about its pivot 101 causing the counterweight arm 104 to swing outwardly from the pawl carrying arm 99 sufficiently to permit the tooth of the pawl to ride over the ratchet. The counterweight 106 will automatically return the pawl to proper engaging position upon each upward stroke of the arm 88. Normally the pawl is held in engagement during the down stroke of the arms 99 and imparts a turning movement thereto, the extent of which depends upon the adjustment of the nut 89. In the event, however, that the rotation of the vane wheel is obstructed, the pawl will ride over the ratchet but, as soon as the obstruction is removed, the vane wheel will be again operated by the pawl.

The cam arm 40 is so designed that the bells 31 and 32 have a relatively rapid opening and closing movement, the bells being closed quickly after the material resting thereon has been discharged. The conical wall 5 of the base section cooperates with the bell 32

to impede the flow of gas from the interior of the producer into the intermediate chamber of the feeder during the discharge of material into the producer. When the bell 32 is opened it moves rapidly down to a position in which the outer edge thereof is in proximity to the conical wall 5 and the material flowing from the intermediate chamber drops down into the space between the bell 32 and the wall 5 forming a seal against passage of gas past the bell 32. As the bell 32 moves upwardly into engagement with the discharge opening 14, the material resting thereon is discharged through the opening 4 into the producer. The bell 32 thus co-acts with the fuel in the passage thereof from the intermediate chamber into the producer to impede the escape of gas during both the opening and closing movements.

Cooperating with the opening 4, in the base of the feeder there is a slide valve 107 which is kept in open position during the operation of the feeder but which may be closed to permit repair of the feeder without discontinuing the operation of the producer. The valve 107 passes through a sand box 108 at one side of the casing which is adapted to receive sand to seal the valve against escape of gas.

If it becomes necessary to repair or replace either of the bells at any time, this may be done without interrupting the operation of the producer by closing and sealing the valve 107 and removing the part 7 of the intermediate section of the casing which will give access to both bells, either of which may be removed through the open side of the casing. It would be noted that the bell operating mechanism is not disturbed either by the removal of the part 7 of the casing or by the removal and replacement of the bells and that, as soon as the part 7 of the casing is replaced after repair or replacement of a bell, the operation of the feeder may be resumed.

Having thus described my invention, what I claim is:

1. A fuel feeder for gas producers comprising a casing adapted to be mounted upon the top of a producer, said casing having a lower chamber with an opening into the producer and an upper chamber having a discharge portion opening into the lower chamber, valves for opening and closing said openings, means for operating said valves alternately and at predetermined intervals, a vane wheel for delivering fuel to the discharge portion of the upper chamber and means for turning said wheel at a predetermined rate.

2. A fuel feeder for gas producers comprising a casing adapted to be mounted upon the top of a producer, said casing having a lower chamber with an opening into the producer and an upper chamber having a dis-

charge portion opening into the lower chamber, valves for opening and closing said openings, a rotary feed device for delivering fuel to the discharge portion of the upper chamber, a rotary actuator adapted to operate said valves alternately, and means for rotating said actuator and said feed device at predetermined rates.

3. A fuel feeder for gas producers comprising a casing adapted to be mounted upon the top of a producer, said casing having a lower chamber with an opening into the producer and an upper chamber having a discharge portion opening into the lower chamber, valves for opening and closing said openings, means associated with the upper chamber for holding a supply of fuel and for providing a regulated delivery of fuel to the discharge portion therof, said means including a rotary vane wheel for delivering the material to the discharge portion of the chamber, actuating members connected to said valves, a rotary cam adapted to alternately operate the actuating members, and means for rotating said cam and said vane wheel at predetermined rates.

4. A fuel feeder comprising a casing having a lower chamber with a discharge opening and an upper chamber with a discharge portion opening into the lower chamber, valves for opening and closing said openings, means for operating said valves alternately and at predetermined intervals, a rotary feed device controlling the rate of delivery of fuel to the discharge portion of the upper chamber, and means for rotating said feed device at various predetermined rates.

5. A fuel feeder comprising a casing having a lower chamber with a discharge opening and an upper chamber with a discharge portion opening into the lower chamber, valves for opening and closing said openings, a rotary feed device for regulating the delivery of fuel to the discharge portion of the upper chamber, means including a rotary actuator for operating said valves alternately, means for rotating said actuator and for rotating said feed device at various rates relatively to the rate of rotation of the actuator.

6. A fuel feeder for gas producers comprising a casing having a base portion adapted to be supported on the cover of a producer and superposed chambers above said base portion, the lowermost chamber having a discharge opening at the bottom therof through said base portion and cover and the chambers above the same each having an opening to the chamber beneath it, bells controlling said last mentioned openings, the lowermost bell being movable within the lowermost chamber above the opening into the producer, and means for operating said bells.

7. A fuel feeder comprising a casing hav-

ing a base portion and superposed chambers with openings at the lower ends thereof, the opening of the lowermost chamber being through the base portion, means for closing said last mentioned opening, bells within the casing for controlling the openings of chambers above the lowermost, and means for operating said bells, said casing having a portion of its wall removable to permit access to said bells for replacement or repair.

8. A fuel feeder comprising a casing having superposed chambers, bells within the casing controlling communication between superposed chambers and means mounted upon the wall of the casing at one side thereof for supporting and operating said bells, said wall having a portion, on the side opposite said supporting means, removable to permit access to said bells for replacement or repair.

9. A fuel feeder comprising a casing having a base portion and a hollow body above said base portion, said hollow body having walls formed to provide a lower chamber, an intermediate chamber and an upper chamber, said intermediate chamber having a restricted portion providing an opening into the lower chamber and said upper chamber having a restricted portion providing an opening into the lower chamber, bells for closing said openings, said bells being mounted for movement downwardly from said openings into the intermediate and lower chambers, respectively, said casing having a portion at one side thereof and forming a part of the wall of the intermediate and lower chambers removable to permit access to both bells.

10. A fuel feeder comprising a tubular casing having a base section with an opening at the lower end thereof, said base section flaring upwardly from the opening, an intermediate section secured upon said base section, the intermediate section having a restricted portion above the lower end thereof and an enlarged upper end portion, an upper section secured to upper end of the intermediate section, said upper section having a restricted portion at its lower end, bells mounted for movement upwardly into the restricted portions to close the same, and means mounted on the casing at one side thereof for supporting and operating the bells, said intermediate section being divided vertically into two half parts, one of which carries part of said bell supporting and operating means and the other of which is removable to permit access to the bells.

11. A fuel feeder comprising a casing having upper and lower superposed chambers provided with discharge openings at the bottoms thereof, a pair of superposed shafts extending horizontally through said casing at one side thereof, an arm fixed to each of said

shafts within the casing, bells suspended from said arms, an arm fixed to each of said shafts outside the casing, a shaft mounted intermediate said first-mentioned shafts, a cam on said shaft engaging said arms, and 5 means for rotating the cam shaft.

12. A fuel feeder comprising a casing having upper and lower superposed chambers provided with discharge openings at the bottoms thereof, a pair of superposed shafts extending horizontally through said casing at one side thereof, an arm fixed to each of said shafts within the casing, bells suspended from said arms, an arm fixed to each of said shafts outside the casing, counterweights connected 10 to the shafts for holding the bells in closing position, a shaft mounted intermediate said first-mentioned shafts, a cam on said shaft engaging said arms, and means for rotating the cam shaft.

13. A fuel feeder comprising a casing having upper and lower superposed chambers provided with discharge openings, valves for opening and closing said openings, counterweights for normally holding said valves in 25 closed position, a shaft having a cam thereon alternately acting on said counterweights to lift the same, means including a pawl and ratchet for operating said cam shaft, and means for preventing overrunning of said 30 ratchet.

14. A fuel feeder comprising a casing having upper and lower superposed chambers provided with discharge openings, valves for 35 opening and closing said openings, counterweights for normally holding said valves in closed position, a shaft having a cam thereon alternately acting on said counterweights to lift the same, means including a pawl and ratchet for operating said cam shaft, and 40 means for preventing overrunning and reverse rotation of said ratchet.

15. A fuel feeder comprising a casing having upper and lower superposed chambers provided with discharge openings at the bottoms thereof, three parallel superposed shafts carried by said casing, the upper and lower of said shafts extending to the interior of the casing, arms fixed to the upper and lower shafts inside the casing, bells suspended 50 from said arms for controlling said openings, a cam on said intermediate shaft, arms on said upper and lower shafts engaging the cam, counterweights connected to said upper and lower shafts for holding the bells in 55 closed positions, means including a pawl and ratchet for operating said cam shaft, and means for preventing overrunning of said ratchet.

16. A fuel feeder comprising a casing having superposed upper and lower chambers with openings in the bottom thereof, valves for opening and closing said openings, operating members connected to the valves, a cam 65 engaging said operating members for alter-

nately operating the valves, a ratchet rotatable with the cam, a movably mounted member carrying a pawl engaging said ratchet, means for reciprocating said pawl carrying member, a rotary feeder for regulating the feed of fuel to the upper chamber, a ratchet connected to said feeder, a pawl engaging said last-mentioned ratchet, and means for actuating said last-mentioned pawl from said reciprocating member.

17. A fuel feeder comprising a casing having superposed upper and lower chambers with openings in the bottoms thereof, valves for opening and closing said openings, means for operating said valves alternately and at predetermined intervals, a rotary feeder for regulating the feed of fuel to the upper chamber, a ratchet connected to said feeder, a pawl engaging said ratchet, and means operated by said valve actuating means for operating said pawl to turn said ratchet.

18. A fuel feeder comprising a casing having superposed upper and lower chambers with openings in the bottoms thereof, valves for opening and closing said openings, means for operating said valves alternately and at predetermined intervals, a rotary vane wheel for regulating the feed of fuel to the upper chamber, means for turning said vane wheel, and means for releasing said vane wheel from its turning means upon an excessive resistance to turning movement.

19. A fuel feeder comprising a casing having superposed upper and lower chambers with openings in the bottoms thereof for passage of fuel, bells controlling said openings, continuously operated means for alternately operating said bells, a vane wheel controlling the flow of material to the upper chamber, means actuated by the bell operating means for turning said vane wheel, and means for rendering said vane wheel turning means inoperative upon excessive resistance to turning movement.

20. A feeder for gas producers comprising a casing adapted to be mounted upon the cover of a producer having a chamber with an opening in the bottom thereof, a bell for closing said opening, a chamber beneath the first chamber enclosing said bell, said lower chamber having an opening into the producer of a diameter less than that of the bell and a conical upwardly flaring wall above the opening, and means for moving the bell upwardly to a position closing the opening of the first-mentioned chamber and downwardly to a position in which the outer edge of the bell is in proximity to the conical wall of the lower chamber.

In testimony whereof, I hereunto affix my 125 signature.

JOHN F. ROGERS.
